United States Patent Office

Des. 203,559
Patented Jan. 25, 1966

203,559

JUG

Bruce L. Roberts, Rossford, Ohio, assignor to Owens-Illinois Glass Company, Toledo, Ohio, a corporation of Ohio

Filed Jan. 27, 1965, Ser. No. 83,604

Term of patent 14 years

(Cl. D58—5)

FIG. 1

FIG. 2

FIG. 3

The side not shown is the same as the side shown. The characteristic features of this design reside in the configuration shown in full lines on the drawings.

I claim:

The ornamental design for a jug, substantially as shown and described.
